(57) **CLAIM**

The ornamental design for a bottle, as shown and described.

DESCRIPTION

FIG. 1 is a front perspective view of a bottle showing our new design;

FIG. 2 is a front elevational view thereof, the left side, right side, and rear elevational views thereof being identical thereto; and,

FIG. 3 is a top plan view thereof.

The broken line showing of a mouthpiece is for the purpose of illustrating only and forms no part of the claimed design.
